(57) **CLAIM**

The ornamental design for a table base, as shown and described.

DESCRIPTION

FIG. 1 is a perspective view of the table base of our new design shown with a table top in broken lines.

FIG. 2 is an enlarged perspective view of the table base of FIG. 1 shown without any table top.

FIG. 3 is a front view of the table base of FIG. 1, the rear view being a mirror image thereof.

FIG. 4 is a left side view of the table base of FIG. 1, the right side view being a mirror image thereof.

FIG. 5 is a top view of the table base of FIG. 1; and,
FIG. 6 is a bottom view of the table base of FIG. 1.

Those portions shown in broken lines are for environmental purposes only and form no part of the claimed design.
